HORIZONTALLY FIRED GAS-OIL BURNER

Cyril Charles Young, Kansas City, Mo.

Application March 12, 1951, Serial No. 215,083

16 Claims. (Cl. 158—91)

1

This invention relates generally to a burner unit of a heating apparatus, and more particularly to a combination gas and oil burner unit which may be fired in a horizontal position.

The subject matter of the present invention constitutes a continuation-in-part of that disclosed in my copending application, U. S. Serial No. 118,243, filed September 28, 1949, now Patent 2,619,159, November 25, 1952.

As a result of the increased use of heating distillates and the increased demand for higher octane fuels, the supply of straight-run, prime-white distillates and blends of straight-run with thermally cracked fuels are insufficient in supplying the needs for such fuels for heating purposes.

One of the most fertile sources of auxiliary fuel to supplement the available supply of heating distillates is from the group of catalytically cracked intermediates. It is well known, however, that the process of catalytic cracking has a tendency to produce a hydrocarbon molecular structure which is changed from the straight chain type to the so-called branch chain, closed ring and olefinic type molecules. Thus, catalytically cracked fuels are in general more difficult to burn than straight-run heating distillates.

In order to provide an improved heating structure which will efficiently burn catalytically cracked fuels, it is necessary to provide a structure which will speed up the combustion reaction so that free carbon particles will be completely burned before they reach comparatively cool regions, thus to avoid soot deposits.

Moreover, in order to successfully burn catalytically cracked fuels a structure must be provided which will retard the process of combustion in its secondary phase to promote what is known as aldehydous type of combustion. In other words, water vapor must be created during the initial stages of combustion to permit hydrogen from the fuel to unite with oxygen from the air thereby providing a so-called "water gas" reaction at high temperatures which will provide the proper atmosphere for soot-free combustion.

According to the general features of the present invention, a horizontally fired burner unit is provided which includes a combustion chamber wherein a part of the incoming combustion supporting air is diluted with flame gases. The flame gases are controlled within the combustion chamber to dilute the air and fuel vapors, a recirculation flow being established in the vaporizer compartment so that recirculation of

2

the combustion gases affords the reuse of such hydrogen as is contained in the fuel and the air.

More specifically, the structure of the present invention comprises a double walled casing forming a vaporization compartment surrounded by an air chamber and having a central core projecting through the vaporizer compartment towards a horizontal burner port. A large number of openings are provided in the casing and are arranged in predetermined alignment to direct converging jets of air from the air chamber into the vaporization compartment, thereby to provide directed movements of preheated air to rapidly stir and mix unburned fuel vapors with gradually increasing quantities of turbulently introduced combustion supporting air. The air movement concurrently stirs in increased quantities of flue gases resulting from prior combustion within the vaporization compartment. Thus, the burner structure provided in accordance with the disclosure contained herein is fully capable of efficiently burning commercially available domestic distillates such as catalytically cracked fuels.

It is, therefore, an object of this invention to provide an improved burner unit which is capable of being fired in a horizontal position.

Another object of the present invention is to provide a burner unit structure which will efficiently utilize catalytically cracked fuels.

Yet another object of the present invention is to provide an improved combination gas and oil burner unit capable of efficiently burning a gas fuel or a low grade distillate.

Many other advantages, features and additional objects of the present invention will become manifest to those versed in the art upon making reference to the detailed description which follows and the accompanying sheets of drawings in which a specific embodiment of the invention is shown by way of preferred example.

On the drawings—

Figure 1 is a front elevational view of a combination gas-oil burner unit according to the present invention;

Figure 2 is an enlarged cross sectional view with parts shown in elevation and with parts broken away of the burner unit shown in Figure 1;

Figure 3 is a fragmentary enlarged cross sectional view with parts removed for the sake of clarity showing the bottom section of the central core projecting through the vaporizer compartment of the burner unit structure according to the present invention;

Figure 4 is a schematic cross sectional view illustrating the flame pattern within the vaporizer compartment; and

Figure 5 is a fragmentary schematic cross sectional view showing the air flow current patterns established within a portion of the vaporization compartment in accordance with the principles of the present invention.

As shown on the drawings—

The burner unit of the present invention is indicated generally by the reference numeral 10 and includes a double wall casing 11 forming a generally cylindrical vaporizer compartment 12, surrounded by an air chamber 13.

The front wall of the compartment 12 is indicated by the reference numeral 14 and is provided with a generally horizontally disposed burner port 16 which is formed by a tapered throat 17 diverging outwardly from the vaporizer compartment 12.

The back wall of the compartment 12 is indicated by the reference numeral 18 and includes a central core 19 formed by two concentrically spaced tubular members joined at one end which project normal to the back wall 18 through the vaporizer 12 toward the burner port 16. Thus, the vaporizer compartment is provided with an annular combustion chamber surrounding a hollow center core.

An air inlet 20 is provided through which pressurized air delivered from a suitable source may be provided to the air chamber 13.

A fuel inlet 21 is passed through the double wall casing 11 and may be connected to a suitable source of supply to maintain an adequate supply of vaporizable fuel such as a catalytically cracked fuel in the bottom of the vaporizer compartment 12. It will be noted that the front wall 14 is provided with an adequate lip which will retain a suitable amount of vaporizable fuel in the bottom of the vaporizer compartment 12.

A gas fuel may be burned in the burner unit 10 in a conventional manner through gas-burner-mixture tubes 22 mounted on a bracket 23 and arranged to be carried in aligned assembly with the inner walls of the central core 19. The gas-burner-mixture tubes are arranged to fire through the burner port 16.

A pilot burner 24 is employed in the burner assembly for the purpose of igniting the gas and oil fuels employed therein. The pilot burner 24 is preferably located in the central core 19 and may comprise a burner-mixer of conventional design to supply a combustible mixture of gas to a first burner port 26 arranged to ignite the gas emanating from the gas-burner-mixer tubes 22 and a port 27 which is arranged to direct a flame towards the supply of fuel in the bottom of the vaporizer compartment 12. The usual plurality of pilot burner ports 28 may also be provided intermediate the port 27 and the port 26 so that the ignition of gas emanating from any one port will ignite the gas emanating from the remaining ports. The pilot burner 24 may be equipped with the usual heat sensitive element 29 for the purpose of cutting out the fuel supply to the pilot valve 24 in the event of failure of the pilot flame.

In operating the burner unit 10 on a gas fuel, the primary combustion supporting air is supplied by means of the usual mixing throat (not shown) provided at the inlet of each burner tube 22 and a secondary supply of combustion supporting air is supplied through the bore 30 provided by the innermost tubular member forming

the central core 19. A tertiary supply of combustion supporting air is furnished through a plurality of ports about to be described in connection with the oil operation of the burner unit 10.

As will be noted upon making reference to the drawings, the vaporizer compartment 12 is of generally cylindrical shape and in this particular embodiment the central core 19 is also of generally cylindrical shape, the two cylindrical elements being eccentrically offset relative to one another so that a combustion chamber is provided between the respective cylinders at the bottom of which the liquid oil fuel may be vaporized and partially burned.

In order to support the combustion of the liquid fuel, a supply of air is forced into the air chamber 13 through the inlet 20 by means of any suitable blower, the structural details of which are not necessary to the understanding of the principles of the present invention.

The lower portion of the central core 19 is provided with a plurality of ports 31 (Figures 2 and 3) which direct radially outwardly directed jets of air downward upon the ignited liquid fuel at the bottom of the vaporizer compartment 12, thereby to promote a rapid vaporization of the liquid fuel.

The inside wall of the double wall casing 11 is also provided with a plurality of aligned ports 32 which are arranged to direct jets of air horizontally over the liquid fuel. The jets of air emanating from the ports 32 intersect the jets of air emanating from the ports 31 thereby creating a turbulence which increases the combustion of the vapors immediately above the level of the supply of liquid fuel.

A plurality of ports 33 are provided in the front wall 14 and are arranged to direct jets of air rearwardly into the vaporizer compartment 12 immediately adjacent the inner surface of the double wall casing 11. The jets of air through the ports 33 not only scrub the inner wall of the casing 11 thereby avoiding carbon deposits thereon, but at the same time assist in circulating the vapors and gases generated in the lower section of the vaporizer compartment 12 toward the back of the vaporizer compartment as the vapors rise in the compartment 12 due to rapid expansion under the effects of combustion.

The inner wall of the double wall casing 11 is provided with a plurality of ports 34 which are arranged to direct the jets of air radially inwardly adjacent the back wall 18. The jets of air moving through the ports 34 not only serve to avoid the accumulation of carbon particles on the back wall 18, but assist in circulating the vapors and gases radially inwardly at the rear of the compartment 12.

The back wall 18 is provided with a plurality of ports 36 which are arranged to direct jets of air horizontally around the central core 19 and directly adjacent the outer periphery thereof. The movement of the air through the ports 36 scrubs the peripheral surface of the central core 19 and also assists in circulating the vapors and gases toward the front of the vaporizer compartment 12.

As will be noted in Figures 4 and 5, the pattern of movement established by the provision of the ports 33, 34, and 36 is essentially a circular swirling motion indicated by the arrows 37.

Adjacent the end of the central core 19, a plurality of ports 38 is provided which are arranged to direct jets of air radially outwardly thereby tending to block the immediate passage

of vapors and gases into the main burner port 16 and also further contributing to the revolving motion of the gaseous mixture within the vaporizer compartment 12. It will be understood that the delaying action will insure a longer exposure of the fuel vapors to the environment of the vaporizer compartment, thereby assisting in bringing about the clean combustion of the liquid fuel.

The central core is provided with a tapered front section 39 in which is formed a plurality of ports 40 arranged to direct jets of air divergently outwardly in the general direction of the burner port 16. The action of the jets of air moving through the ports 40 is to further delay the exit of burning vapors from the vaporizer compartment 12 in order that the vapors can be further churned and stirred in with gradually increasing quantities of preheated air, thereby to further promote the clean and complete combustion of the combustible vapors.

The tapered section 39 of the central core 19 terminates in a radially extending wall 41 having formed therein a plurality of ports 42 arranged to direct jets of air horizontally through the burner port 16. The movement of air through the ports 42 completes the supply of combustion supporting air to the inside core of the burning oil vapors, and in addition, insures that an additional supply of secondary air may be provided through the bore 38 of the central core 19 through an induction flow. Thus, a core of fresh air is maintained adjacent the burner port 16 for the final combustion of any unburned vapors and gases. Moreover, since the core of combustion supporting air is induced to flow horizontally through the burner port 16, the gas-burner-mixture tubes 22 are ventilated and cooled thereby and the possibility of damage to the tubes 22 is minimized.

The tapered throat 47 surrounding the burner port 16 is provided with a plurality of ports 43 which are arranged to direct jets of air forward and inward into the burning vapors, thereby to assist in completing the combustion of all vapors located near the outside of the circular band of burning vapors moving through the burner port 16.

As is shown in Figures 1 and 2, the particular embodiment herein disclosed additionally utilizes an L-shaped inspirator nozzle 46 which has one leg passing through the inner wall of the double wall casing 11 to establish communication with the air chamber 13 and the other leg arranged to lie approximately on the central line of the central core 19. A plurality of ports 47 are provided in the end of inspirator nozzle 46 and are arranged to project jets of air horizontally forward through the center of the main burner port 16, thereby giving additional protection to the gas-burner-mixture tubes 22 and further supplementing the supply of combustion supporting air directly to the center of the core of burning vapors moving through the burner port 16.

As will be noted in Figures 2 and 3, a plurality of ports 48 are located around the margin of a notch 49 formed in the central core 19 to accommodate one leg of the pilot burner 24. Movement of air through the ports 48 effectively blocks the passage of burning oil vapors into the central core 19.

The combined effect of the various groups of air jets moving into the vaporizer compartment 12 produces an intense, concentrated fire di-

rectly above the level of the liquid fuel in the bottom of the vaporizer compartment 12 so that a relatively rapid vaporization of the liquid fuel occurs. The burning vapors move in a generally spiral path backward and forward within the vaporizer compartment 12 on both sides of the central core 19 as the vapors rise from the supply of liquid fuel to eventually fill the entire vaporizer compartment 12 before discharge through the main burner port 16.

It has been found that the burner unit provided in accordance with the principles of the present invention is particularly efficient and can be effectively employed in connection with commercially available domestic distillates such as a catalytically cracked fuel. The combustion air is highly preheated while passing through the narrow passages forming the air chamber 13 and the gaseous products of combustion from the initial stages of combustion are recirculated to promote an especially effective stirring action as well as to permit the use of such hydrogen as is contained in the fuel and the air within the vaporizer compartment 12.

The air jet pattern rapidly stirs and mixes unburned fuel vapors with gradually increasing quantities of preheated air and also stirs in increased quantities of flue gases throughout the combustion cycle.

It will be understood, of course, that a person skilled in the art might suggest various minor modifications to the preferred structural embodiment herein described by way of illustrative example only; however, I do not propose to be limited to the precise details set out for the sake of clarity but wish to embrace within the scope of this patent all such modifications as reasonably and properly come within the scope of my contribution to the art.

I claim as my invention:

1. In a burner unit, casing means forming a generally cylindrical vaporization compartment, said casing means having one end wall having an opening to form a horizontally disposed burner port for the compartment and the opposite end wall having a tube projecting into said compartment to divide said compartment into an annular combustion chamber with a hollow center core, and means to provide a supply of vaporizable fuel to the lower portion of said vaporization compartment, said tube having a plurality of ports formed in the bottom portion thereof arranged to direct jets of air downward toward the fuel in the lower portion of said vaporization compartment, said casing means having a plurality of horizontally aligned ports in the lower portion thereof arranged to direct jets of air over the surface of the fuel, said one end wall having a plurality of ports arranged to direct jets of air backward into the vaporizer compartment, said opposite end wall having a plurality of ports arranged to direct jets of air forwardly through said vaporizer compartment, whereby vapors arising from the oil will be thoroughly churned throughout the annular combustion chamber before exit therefrom through the burner port.

2. A horizontally fired burner unit comprising a double wall casing forming a vaporization compartment surrounded by an air chamber and having an upright front wall provided with a horizontal burner port for the vaporization compartment, a back wall for said compartment, having a portion projecting through said compartment towards the burner port and forming a central

core in said vaporization compartment, and means to maintain a supply of vaporizable fuel in said compartment, said casing having openings formed therein to direct combustion supporting air from said air chamber into said compartment.

3. A burner unit as defined in claim 2, said central core being provided with openings arranged to direct jets of air downwardly towards the bottom of said compartment for rapid vaporization of fuel.

4. A burner unit as defined in claim 3, said front wall having ports aligned to direct jets of air backward into said compartment to scrub said walls of said compartment adjacent said front wall and to direct vapors rearwardly in said compartment.

5. A burner unit as defined in claim 4, said back wall having ports aligned adjacent said core to scrub the peripheral walls thereof and to direct jets of air forwardly in said compartment.

6. A burner unit as defined in claim 5, said core having ports adjacent the end thereof to direct jets of air radially outwardly for churning vapors in said compartment and delaying passage of burning gases into the burner port.

7. A burner unit as defined in claim 6, said front wall having a tapered throat at said burner port diverging outwardly from said compartment, said tapered throat having ports arranged to direct jets of air forward and inward into the burning vapors passing through said burner port.

8. A burner unit as defined in claim 7, and a jet nozzle in said core connected to said air chamber and having openings arranged to direct jets of air into the center of the burner port.

9. A burner unit as defined in claim 2, said central core being provided with openings to direct jets of air towards the bottom of said compartment for rapid vaporization of fuel, whereby an intense concentrated combustion of vapors may occur above the level of said fuel in said compartment.

10. A burner unit as defined in claim 9, said front wall, said back wall and said central core each having ports aligned to turbulently stir vapors arising around said central core with combustion supporting air preheated by initial combustion in said compartment.

11. A burner unit as defined in claim 9, said core having openings formed therein to direct jets of air radially outwardly to delay passage of combustion gases and vapors through said burner port.

12. A burner unit as defined in claim 11, said front wall having a tapered throat at said burner port diverging outwardly from said compartment and being provided with openings in said throat arranged to direct jets of air into the burning vapors passing through said burner port.

13. A burner unit as defined in claim 2, said casing having openings in spaced apart alignment to direct jets of air into said vaporization compartment tending to move burning vapors arising from the supply of fuel in said compartment in a generally spiral path backward and forward within the vaporizer compartment around said central core, thereby to completely fill said vaporizer compartment before discharge of the vapors through said burner port.

14. A burner unit comprising a double wall casing forming a vaporizer compartment surrounded by an air chamber, a front wall for said compartment having an opening therethrough forming a horizontally disposed burner port, a rear wall for said compartment including a portion extending inwardly into said compartment toward said burner port and constituting a double wall hollow center core, and means to maintain a supply of vaporizable fuel in the lower portion of said vaporizer compartment, said rear wall, said casing, said front wall and said core each having a plurality of ports to direct jets of air from the air chamber into the vaporizer compartment, said ports aligned with respect to one another to direct the jets of air in different directions and thereby to circulate the vapors arising from the supply of fuel in the compartment in a generally spiral path backward and forward within the vaporizer compartment around said central core, thereby to completely fill the vaporizer compartment before discharge of the vapors through the burner port.

15. A horizontally fired combustion burner unit comprising, a double wall casing forming a generally cylindrical vaporization compartment having a horizontal axis, a front wall for said compartment having a horizontal burner port therein, a back wall for said compartment, a pair of concentrically spaced tubular members joined at one end, said tubular members being generally normal to said back wall and projecting in the direction of said horizontal axis toward said burner port to form a center core surrounded by an annular combustion cavity in said compartment, said double wall casing providing an air chamber adjacent the vaporization compartment, means to maintain a supply of vaporizable fuel in the lower portion of said vaporization compartment for vaporization in said annular combustion cavity, said double wall casing having a plurality of ports formed therein directing combustion supporting air from said air chamber into said combustion chamber.

16. A horizontally fired burner unit comprising a double wall casing forming a generally cylindrical vaporization compartment having a horizontal axis and surrounded by an air chamber and having a front wall provided with a horizontal burner port for the vaporization compartment, a back wall for said compartment having a cylindrical core projecting in the direction of said horizontal axis towards the burner port to provide an annular combustion chamber in said compartment, means to maintain a supply of vaporizable fuel in said compartment, and said casing having openings therein to direct combustion supporting air into said compartment from said air chamber.
